MOTION PICTURE CAMERA HOUSING

Donald L. Coakley, Golden, Colo.

Filed Dec. 18, 1961, Ser. No. 67,929

Term of patent 14 years

(Cl. D61—1)

FIG. 1

FIG. 2

FIG. 3

FIG. 4

FIG. 5

FIG. 6

FIG. 7

FIG. 1 is a bottom, right-side perspective view of a motion picture camera housing showing my new design;

FIG. 2 is a left-side elevational view thereof;

FIG. 3 is a front elevational view thereof;

FIG. 4 is a right-side elevational view thereof;

FIG. 5 is a rear elevational view thereof;

FIG. 6 is a top plan view thereof; and

FIG. 7 is a bottom plan view thereof.

I claim:

The ornamental design for a motion picture camera housing, substantially as shown.
